UNITED STATES PATENT OFFICE.

LEWIS A. DOWNS, OF CHICAGO, ILLINOIS.

CORSET.

SPECIFICATION forming part of Letters Patent No. 244,385, dated July 19, 1881.

Application filed January 8, 1881. (Model.)

To all whom it may concern:

Be it known that I, LEWIS A. DOWNS, of Chicago, in the county of Cook and State of Illinois, have invented certain new and useful 5 Improvements in Corsets; and I do hereby declare the following to be a full, clear, and exact description of the invention, that will enable others skilled in the art to which it appertains to understand and make use of the same, 10 reference being had to the accompanying drawings, and to letters of reference marked thereon, forming a part of this specification.

The object of this invention is an improvement in the manufacture of that portion of the 15 corset which lies nearly or immediately over the hips, the parts being so constructed and united as to afford ease and comfort to the wearer, and at the same time retain the symmetrical proportions of the fabric.

20 Figure 1 is a partial front and side elevation of a corset embodying my improvement. Fig. 2 is a separate view of the hip portion, to which my improvement more nearly relates. Fig. 3 is a transverse section in the plane 3 3, Fig. 2; 25 and Fig. 4, an edge view of the corded waist-piece.

Referring to the drawings, A represents the side or hip section of a corset; *a a'*, rubber or elastic gores, and *b* the corded waist portion 30 or center piece. The hip-section referred to is composed of three distinct pieces, the upper elastic gore forming one piece, the lower elastic gore another, and the corded waist part the third piece. These several parts are then sewed 35 together, being arranged in the order shown in Fig. 2 of the drawings, and are then inserted in the corset, uniting the front and back portions of the same, substantially as illustrated in Fig. 1 of the drawings. This form of construction was found to be necessary in order 40 to preserve a due proportion of the several parts relative to each other. The corded waist-piece is really the essential feature of my improvement. It readily conforms to the movements 45 of the wearer and retains the symmetry of the parts without any inconvenience to the wearer.

The corded seams running in a horizontal plane, instead of taking a vertical course, allows this portion of the corset to double over without breaking the stiffening fabric, for the reason 50 that the fabric between each cord acts as a flexible joint, readily allowing the wearer to bend over, and when the person assumes an erect position the waist portion returns to its proper position relative to the joining parts. This 55 corded waist-piece may be thickened or stiffened with any fabric that may be suitable for the purpose, and in accordance with the requirements of the manufacture. All hard stiffening material—such as whalebone, horn, &c.—60 is, however, entirely dispensed with in this portion of the corset. If whalebones are used which run the whole length of the hip-section, they very soon break. If short bones are used running from the top and bottom, the inner 65 ends prove to be very uncomfortable to the wearer when in the act of bending over. If the bones are run in a diagonal direction, they very naturally soon force their way through the fabric of the corset, all of these features 70 being very objectionable, and which are entirely removed by my improvement. The corded waist-pieces have a slight vertical movement, just sufficient for the purpose, and the rubber gores a lateral adjustment, the combined effect of which is to give ease and comfort to the person without any of the discomforts or objections enumerated above.

Having thus described my invention, what I 75 claim, and desire to secure by Letters Patent, 80 is—

In the side section of a corset, the corded waist or center piece, *b*, and the parts *A A'*, having elastic gores *a a'*, all joined together and inserted in the corset, uniting the front and 85 back sections, substantially as and for the purpose set forth.

LEWIS A. DOWNS.
